UNITED STATES PATENT OFFICE.

MAURICE L. KNIGHT, OF BALTIMORE, MARYLAND.

MAUSOLEUM.

979,965.

Specification of Letters Patent. Patented Dec. 27, 1910.

Application filed May 14, 1910. Serial No. 561,415.

To all whom it may concern:

Be it known that I, MAURICE L. KNIGHT, a citizen of the United States, residing in the city and county of Baltimore, State of Maryland, have invented a new and useful Mausoleum, of which the following is a specification.

My invention consists of improved means for obtaining ventilation and drainage of the crypts or loculi in a mausoleum or vault.

It further consists of improved means for closing and sealing the crypts or loculi in a vault or mausoleum.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a mausoleum embodying my improvements. Fig. 2 represents a longitudinal vertical section of the same. Fig. 3 represents a horizontal section of the mausoleum. Fig. 4 represents a transverse vertical section on the line $x-x$ of Fig. 3. Fig. 5 represents a sectional detail view of a shutter and its fastenings of one of the crypts or loculi. Fig. 6 represents a horizontal section of a window.

Similar numerals of reference indicate corresponding parts in the figures.

Referring to the drawings:—The mausoleum has a suitable foundation, 1, upon which the side walls, 2, and the front wall, 3, and rear wall, 4, are supported. A porch or portico is formed at the front by columns, 5, and the frieze, 6, overhangs such porch at the front. Gable stones, 7, are supported upon the frieze at the front and rear, and have each two tenons, 8, upon each of their inclined top-edges. Two roof-stones, 9, of stone, metal or composition, are slantingly supported at their ends upon the slanting edges of the gable-stones, and have mortises, 10, engaging the tenons upon the same. At

the eaves, the roof stones or slabs are supported upon slanting fillers, 11, which may be integral with the frieze-stones. A cap-stone or ridge stone, 12, rests upon the inner or upper edges of the roof-stones with its side-lips, 13, overlapping such edges. The interior of the mausoleum has a floor, 14, of tiles or any suitable or desired material and construction.

A door, 15, is provided in the front wall 65 of the mausoleum and opens into a transverse vestibule, 16, extending the full width of the structure. A longitudinal corridor, 17, extends rearward from the vestibule, between the crypts or loculi, 18, and window 70 openings 19—19, and 20, are provided respectively at the ends of the vestibule and of the corridor. Said windows have each a rigid grille, 21, at the outside, an intermediate inwardly-swinging storm-window, 22, 75 and an inner, inwardly-swinging air-window, 23, of stained or colored glass or otherwise ornamented. The crypts or loculi for the reception of the coffins or caskets and on both sides of the corridor, are formed 80 from horizontal shelves or slabs, 24, preferably of slate or composition, and faced at the edges which present to or face the corridor, with strips, 25, of marble or other ornamental material. The slabs or shelves 85 are vertically spaced by end walls or slabs, 26, and back walls or slabs, 27, suitably secured to the shelves and to each other. The rear edges of the shelves are cut away to form rectangular openings, 28, and the back-slabs are supported at a distance from the walls of the structure and at the edges of 90 such openings, so that vertical air-chambers or flues, 29, are formed between such walls and slabs. These openings extend along the 95 greater portion of the length of the slabs and register vertically, so that the air-chambers will be wide and unobstructed. Vent-openings, 30, are formed at the lower and upper ends of these air-chambers and through 100 the walls, so as to provide air-circulation up through said chambers. The back-slabs have openings, 31, at their upper and lower edges, communicating with the air-chambers or flues, to provide ventilation at the top 105 and bottom of each crypt or loculus, and drainage from the bottom of the same and said openings extend for more than one-half of the length of the back-slabs, so as to afford free ventilation and drainage to the 110

wide air-chambers, and the openings register with those of the shelves so as to directly communicate with the same. A ceiling-slab or slabs, 32, is supported to cover the vestibule and corridor, and one or more rods, 33, are secured in the ridge-stone and passed through the ceiling-slab and have each an eye, 34, at its lower end. The rod or rods may serve as an auxiliary support for the 10 ceiling-slab and serve to support a hoisting device for raising the caskets to the upper loculi. The fronts of the crypts or loculi are each closed by a shutter, 35, preferably a slab of marble or other ornamental material, and the upper and lower edges of the shutter engage respectively grooves, 36 and 37, in the shelves or slabs, the upper one, 36, of which is deeper and slightly wider than the lower groove, so as to permit the upper 15 edge of the slab to first engage the upper groove, as indicated in dotted lines in Fig. 5, and move upward in the same until the lower edge can drop into the lower groove, when both edges are held in the grooves, 20 whereupon the shutter may be sealed by grouting or pointing with cement or mortar. The back edges of the shelves are secured in the inner faces of the walls and interlock with them excepting at the openings forming 25 the air flues.

By providing the air duct between the crypts or loculi and the wall of the vault or mausoleum structure, by providing such duct with inlet and outlet at the lower and 30 upper ends, and by forming the back walls of the crypts or loculi with openings at their top and bottom edges, communicating with such air duct, I provide perfect circulation and ventilation from the loculi through the 35 ducts, over the ceiling-slab and out to the surrounding atmosphere, thereby disposing of all odors and gaseous effluvia from the contents of the loculi and keeping the interior of the structure pure. All liquid effluvia 40 may pass out from the loculi through the bottom openings into the ducts and be conducted away from the same. By providing the transverse vestibule and the windows at the ends of the same and the corridor, the interior of the structure may be 45 perfectly ventilated and lighted. The storm windows are preferably of clear glass and, together with the grilles, protect the ornamental art windows. The rod or rods depending from the ridge stone may form additional support for the ceiling slab or slabs 50 besides serving as support for hoisting apparatus when a casket is placed in one of the upper loculi. By connecting the space 55 under the roof and above the ceiling with the air ducts, such space will be ventilated and maintained dry, even should moisture leak through the seams of the roof. The shutters of empty loculi will be held in 60 place in their grooves without the use of 65

cement or other fastening means and it is only necessary to seal the shutters as the loculi become occupied.

Having thus described my invention, what I claim as new and desire to secure by Letters Patent, is:—

1. In a vault or mausoleum structure, horizontal shelves having their back edges secured in a wall of the same and formed with openings at said edges, vertical back walls 75 and end walls between said shelves to form crypts or loculi, and said back walls supported to form together with the openings an air duct between them and a wall of the structure and formed with openings into 80 said duct at their top and bottom edges, an inlet and outlet at the ends of such duct, and shutters closing the fronts of such crypts or loculi.

2. In a vault or mausoleum structure, horizontal shelves having their back edges secured in a wall of the same and formed with openings at said edges, vertical back walls 85 and end walls between said shelves to form crypts or loculi, and said back walls supported to form together with the openings an air duct between them and a wall of the structure and formed with openings into 90 said duct at their top and bottom edges, and an inlet and outlet being provided at the 95 lower and upper end of such duct.

3. In a vault or mausoleum, a roof having a ridge-stone, opposed series of vertically arranged loculi, a ceiling slab supported upon the top of said loculi and spanning the 100 space between them, and a rod secured in the ridge-stone at its upper end and having an eye at its lower end bearing against the underside of the ceiling slab to support the same and serve to attach suitable hoisting 105 mechanism.

4. In a vault or mausoleum, horizontal shelves having their rear edges secured in the inner face of a wall of the same and having rectangular openings at said edges 110 extending for the greater portion of the length of the same and registering vertically, and vertical side and back walls forming loculi between said shelves having their back walls secured at the inner edges of the openings in the shelves to form a vertical air-chamber between the back-walls and the wall of the mausoleum and through said 115 openings, the wall of the mausoleum having openings at the top and bottom of the air-space.

5. In a vault or mausoleum, horizontal shelves having their rear edges secured in the inner face of a wall of the same and having openings at said edges and registering vertically, vertical back walls and side walls forming loculi between said shelves having their back walls spaced from the wall of the mausoleum vault to form a 125 vertical air-chamber.

6. In a vault or mausoleum, horizontal shelves having their rear edges secured in the inner face of a wall of the same and having openings at said edges, and registering vertically, vertical back walls and side walls forming loculi between said shelves having their back walls spaced from the wall of the mausoleum vault to form a ver-

tical air chamber, said chamber being provided with ventilating openings at its top 10 and bottom.
